UNITED STATES PATENT OFFICE.

JAMES F. GILLILAND, OF INDIANAPOLIS, INDIANA, ASSIGNOR TO JOHN B. BENNETT AND AUGUST B. MEYER, BOTH OF SAME PLACE.

INSULATOR FOR LINE-WIRES OF MECHANICAL TELEPHONES.

SPECIFICATION forming part of Letters Patent No. 296,330, dated April 8, 1884.

Application filed June 26, 1883. (No model.)

To all whom it may concern:

Be it known that I, JAMES F. GILLILAND, of the city of Indianapolis, county of Marion, and State of Indiana, have invented certain new and useful Improvements in Insulators for Line-Wires of Mechanical Telephones, of which the following is a specification.

The object of my said invention is to produce an "insulator" or means of suspension for the line-wire of mechanical telephones which will confine the voice sounds to the wire, and also prevent said wire from "taking up" other sounds from the objects to which it is secured. This object is accomplished by constructing such an insulator composed of a piece of wire or cord and a piece of dense non-resonant material attached thereto and held in close contact therewith.

One great advantage arising from the use of my insulators or means of suspending the line-wire is that it is possible to bind said line-wire tightly with the wire forming part of said insulators without destroying or impairing its capacity to transmit sound. This has heretofore been impossible, for the reason that in the transmission of sound by the mechanical vibration of the wire the sound, or a considerable portion thereof, will leave the wire at the first point to which it is firmly attached, unless cut off in some way, and previous means of suspension, being as good conductors of sound as the wire itself, have been practicable only when attached to the wire loosely. My means of suspension, being composed in part of dense non-resonant material, cuts off the sound from the wall or post to which it is secured, and therefore may be connected firmly to the wire. By this means the line-wire may be drawn tight and securely fastened to each point of attachment before proceeding to the next, which is a great convenience in stringing wires, especially long wires.

Referring to the accompanying drawings, which are made a part hereof, and on which similar letters of reference indicate similar parts, Figure 1 is a general view of apparatus embodying my improved insulator as I prefer to make it; Fig. 2, a detail view of the insulator on an enlarged scale; Fig. 3, a view of an alter-

nate construction; and Fig. 4, a view similar to Fig. 3, except that one-half the insulator is removed.

In said drawings, the portions marked A represent the line-wire of a mechanical telephone; B, the wire forming part of the hanger, and C the insulator proper, or piece of non-resonant material, forming the other part thereof. The line-wire A connects the telephones in the usual manner. It forms no part of the present invention, though I prefer to use the wire described in Letters Patent No. 255,174, issued to James A. Lakin under date of March 21, 1882, or an improved wire devised by myself, rather than the common kind, as it produces better results.

The wire or cord portion B of the hanger is preferably the same kind of wire as the wire A. It is attached to said wire A at one end, and to a bracket, B', upon the poles, buildings, or whatever structure forms a support for the line.

The insulator proper, or piece of non-resonant material, C, is usually of cast metal, and preferably of substantially the form shown in Fig. 2. In this case the wire B is looped around the wire A, passed through the eye c of said insulator, around the body thereof, through the eye c', and to the bracket B', where it is secured. In the alternate construction shown by Figs. 3 and 4 the wire is passed from the wire A to the bracket B', as before; but the insulator C, being in two pieces, is applied by placing one piece on each side of the wire, and then securing said pieces together by screws c", as shown.

The operation of my said invention, as proved by many and varied practical tests, is to cut off those sounds which, in the ordinarily-constructed mechanical-telephone lines, have come in from the poles, &c., and have been the source of so much annoyance, and to prevent the voice sounds, which it is desired should be conveyed, from passing off or becoming dissipated during the course of transmission.

It will be readily seen, upon an examination of the drawings, that the insulator C is a dead weight upon the hanger B, and is not placed in tension at all. Almost any material in this

position is calculated to interrupt sound more or less effectively, and nearly all materials to a great degree. By selecting the material (cast metal and especially cast-lead I have 5 found superior for the purpose) the sound is so nearly entirely interrupted as to practically perfectly "insulate" the wire from the structure to which it is suspended.

Having thus fully described my said invention, what I claim as new, and desire to secure 10 by Letters Patent, is—

1. The combination, with a mechanical-telephone line-wire and the structures by which it is supported, of a hanger composed of wire 15 or cord running from said line-wire to said structure, and an insulator secured to said wire

in close contact therewith, substantially as set forth.

2. The combination of the wire A, the structures by which the same is supported, and the 20 hangers by which said wire is connected to said structures, said hangers being composed of wires B and insulators C, having eyes c' c', through which said wires pass, substantially as shown and specified. 25

In witness whereof I have hereunto set my hand and seal, at Indianapolis, Indiana, this 19th day of June, A. D. 1883.

JAMES F. GILLILAND. [L. S.]
In presence of—

E. W. BRADFORD,
C. L. THURBER.
